(57) **CLAIM**

I claim the ornamental design for a pistol, as shown and described.

DESCRIPTION

FIG. 1 is a left side of a pistol, showing my new design; FIG. 2 is a left side view of the pistol shown in FIG. 1; FIG. 3 is a top view of the pistol shown in FIG. 1; FIG. 4 is a bottom view of the pistol shown in FIG. 1; FIG. 5 is a front view of the pistol shown in FIG. 1; and, FIG. 6 is a rear view of the pistol shown in FIG. 1. The broken lines in the figures form no part of the claimed design.
